UNITED STATES PATENT OFFICE.

ARTHUR MELVIN LEIGHTON, OF BROCKTON, MASSACHUSETTS, ASSIGNOR TO
JAMES E. MAYNADIER, TRUSTEE, OF TAUNTON, MASSACHUSETTS.

HINGED LAST.

SPECIFICATION forming part of Letters Patent No. 668,196, dated February 19, 1901.

Application filed August 5, 1898. Serial No. 687,763. (No model.)

To all whom it may concern:

Be it known that I, ARTHUR MELVIN LEIGHTON, of Brockton, in the county of Plymouth and State of Massachusetts, have invented 5
an Improved Hinged Last, of which the following is a specification, reference being had to the accompanying drawings, in which—

Figure 1 is a sectional elevation showing my last upon its key-stand and unlocked. 10 Fig. 2 is a section on line 22 of Fig. 1. Fig. 3 is a detail view showing the key retracted and locked in its inoperative position.

My invention relates to improvements in hinged lasts; and the objects of my improvements are, first, to provide a means for automatically locking the last rigidly at the hinged joint, and, second, to provide a simple means for unlocking the last, so that the parts may be swung freely upon the hinge. 15

20 In the drawings, A is the fore-part piece, and B the heel-piece, of the last, fastened together at the hinged joint D by the pintle d, which passes through pintle-holes in the knuckles of the hinge. The shanks a and b 25 of the hinge are made in the form of short tubes and are secured in the longitudinal sockets a' and b', formed in the pieces A and B, respectively. The heel-piece B is formed with a second socket b³, which opens at its 30 lower end into the socket b', and the axes of the sockets b' and b³ are at right angles to each other. The front portion of the socket b³ is formed with a slot b⁴ to receive the key F, while the main portion of the socket b³ is 35 formed to receive the spindle e. Within the socket b' slides the releasing-bolt b², and within the socket a' slides the locking-bolt a², which is slotted longitudinally to receive the pintle d. At one end of the socket a' is 40 the spring a³, which acts to force the locking-bolt a² longitudinally along the socket a' into the socket b'. When the joint D is closed, as shown in Fig. 1, the two sockets a' and b' register axially and form one continuous socket to receive the locking-bolt a². A 45 bracket E is fastened to the work-bench G and carries the spindle e and spring e'. The key F slides in a hole in the bracket E, by which it is guided and bears against the 50 spring e' by means of the pin f, extending through the key-shank f². The spring e' is

inclosed in a tube J, which passes through the work-bench G and is formed with a slot j, in which the pin f slides and by means of which the key F is kept in its operative position. A recess j' in one of the walls of the slot j receives the pin f when the key F is retracted and held with the key-bit f' turned in its inoperative position. (See Fig. 3.)

The last being locked by the locking-bolt a² extending into the socket b' and the key F being in the position shown by the dotted lines in Fig. 1, to unlock the last the operation is as follows: The key F is inserted in the socket b³ until its bit f' bears against the releasing-bolt b². The key F is then pressed down against the force of the spring e' until the spindle is inserted in the socket b³. The key F is forced into the slot b⁴ and the key-bit f' into the socket b' against the releasing-bolt b², which abuts against the locking-bolt a². The locking-bolt a² is thus forced out of the socket b' against the tension of the spring a³. The parts are then as shown in Fig. 1, and the fore-part piece A may now be swung upon the hinge about the pintle d. Upon turning the fore-part piece A so as to close the joint D and raising the last so as to release it from the key F the last will be automatically locked by the locking-bolt a² being forced into the socket b' by the spring a³. 75

80 The main features of my invention are the simple locking device, which is automatic and positive in its action and which cannot become unlocked during any of the operations through which the shoe is passed, and the simple means for unlocking the last.

What I claim as my invention is—

1. A hinged last comprising two hollow shanks united to form a hinge, one shank secured to the heel portion and the other shank secured to the toe portion; and a locking-bolt sliding in one shank and projecting into the other to lock the two shanks when in line, substantially as described. 90

2. A last made up of a heel and toe portion, a hinge connecting those portions; a bolt sliding in one portion of the last, a socket to receive one end of the bolt in the other portion; means to automatically move the bolt to engage the socket, and a key to disengage the bolt from the socket, and a spin- 95

dle to force the key home and to hold the last fast when unlocked substantially as described.

3. A last made up of a heel and toe portion, a hinge connecting those portions, a socket in the toe portion, a bolt in the heel portion; a key; a spindle, and a socket in the heel portion to receive the spindle and key and means to automatically cause the bolt to engage the socket, substantially as described.

4. In a hinged last, a hinge formed with hollow shanks; a bolt slotted to receive the hinge-pintle and sliding within one of the hollow shanks; and means to automatically move the bolt to engage in the other hollow shank thereby locking the last substantially as described.

ARTHUR MELVIN LEIGHTON.
